OLEFIN PRODUCTION PROCESS

Valentine Mekler, Hastings on Hudson, and August H. Schutte, Jackson Heights, N.Y., and Karl J. Korpi, Altadena, Calif., assignors to The Lummus Company, New York, N.Y., a corporation of Delaware

Application January 17, 1955, Serial No. 482,031

6 Claims. (Cl. 208—54)

This invention relates to improvements in apparatus for the production of gaseous olefins from heavy residual hydrocarbons such as asphalt, tars and heavy reduced crudes.

In Schutte's Patent No. 2,526,696, the advantages were disclosed of carrying out the conversion of heavy oils to olefins by a two-stage cracking process wherein the oil was first subjected to a liquid phase, relatively low temperature cracking to produce a maximum amount of low carbon residue, vaporous products and simultaneously convert the heavy carbon forming constituents of the oil into coke, followed by a short-time high temperature cracking of the gaseous and vaporous products from the first reaction to produce maximum yields of valuable olefins.

Such a method represented a significant improvement over previous processes for the high temperature cracking of residual oils wherein these oils were charged directly to the high temperature olefin producing pyrolytic zone. The direct application of the heavy oil inevitably resulted in carbon formation on the heating surfaces, tar formation and the production of undesirable quantities of finely divided carbon and oil soot, resulting in low olefin yields and in operational difficulties. In many cases, these operations have also been hampered by the necessity of providing for burning off of the carbon deposit after a very short on-stream period, the heat evolved usually being in excess of the process heat requirements.

In the co-pending application of Schutte, Serial Number 440,321, filed June 30, 1954, now Patent No. 2,789,084 an improved version of the two-stage cracking of heavy oils to olefins is disclosed, one feature of which is to obtain a greater degree of independence between the operating conditions in the coking zone and in the vapor phase cracking zone. In this application, as in the previous patent 2,526,696, the vapor phase cracking was carried out by passing the vapors from the coking zone through a relatively shallow bed of highly preheated solid particles and providing the endothermic cracking heat by circulating these particles through a reheating zone.

In the present invention, following a preliminary coke removal, the coking zone vapors are cracked in regenerative furnaces which are used in pairs to give continuous flow, each furnace utilizing stationary refractory masses for heat storage and operating with cyclic re-heating. This method has several advantages. It obviates the necessity for circulating highly preheated heat carrier particles. It permits the easy recovery of the heat given up by the quick quenching of the vapor phase cracking product and it provides a means of obtaining extremely short cracking time, all of which are inherently difficult to achieve in a system of circulable solids. Furthermore, by introducing the entire overhead of the coker including gas, gasoline and gas oil fractions into the regenerative furnace without fractionation or condensation, the ethylene yields are unusually high with a very economical ultimate cost.

2

A further advantage of this sequence of operations is the avoidance of many of the problems of gas cleanup after cracking by conventional means. The products from such a cracking zone include suspended carbon, tars, heavy aromatics, heterocyclic compounds and easily polymerizable diolefins. Regardless of the type of final recovery and purification chosen for the major olefinic products these heavier materials must be removed prior to the recovery step in order to prevent fouling of equipment, gumming up of heat surfaces and like problems. In the initial cleanup of the gases, even at low pressures, the temperatures prevailing in the bottom section of the absorption and rectification equipment are high enough to produce fouling and polymerization and most designs merely localize the operational difficulties in this preliminary cleanup step. The combination of processing steps disclosed in the present invention makes it possible to eliminate these difficulties while simplifying the recovery system and improving its economy and heat recovery.

The principal object of the present invention is to integrate a coking system, a regenerative furnace system and a recovery and purification system whereby low cost residual oil is converted into useable coke and a maximum yield of gaseous olefins under readily controlled conditions and at a minimum cost of end products.

A still further object of our invention is to integrate a coking system with regenerative furnaces and fractionation apparatus whereby optimum temperatures and pressures may be employed in all parts of the system with maximum heat recovery, whereby the products from each section of the system may be most effectively utilized for the production of maximum yields of ethylene and/or acetylene.

Further objects and advantages of our invention will appear from the following description of a preferred form of embodiment thereof taken in connection with the attached drawing which is a flow diagram illustrative of one form of apparatus for carrying out the invention.

The integrated unit more particularly shown may be more effectively understood if it is considered to include several sections as follows:

The first major section is the coker or decoking section, wherein the residual carbon and the heavy ends are removed from charging stock. As will be understood hereinafter, the selected removal of certain constituents of the heavy residue of such charging stock is particularly helpful for subsequent processing of lighter hydrocarbons thus produced.

The second major section includes regenerative cracking furnaces of which several examples are known, but in which the Wulff type is preferred. It is in this section that the gas, gasoline, and gas oil overhead from the coker plus steam are economically converted to high yields of olefins.

A third section may be considered to be the gas cleanup section and this includes the removal of aromatics in one step and the treatment for the removal of acidic gaseous constituents particularly H_2S and CO_2 .

If desired, a fourth section may be used in which acetylene is converted to ethylene by suitable catalytic methods, particularly where high yields of ethylene are required with a minimum of acetylene contamination.

The final stage of the apparatus includes fractionation equipment which also may be of well known type in which the specific olefins are recovered as desired.

The foregoing stages of the apparatus are hereinafter described in greater detail:

Coker section

The lowest cost olefin product is economically made from the lowest cost raw material and whereas it has been common practice to produce olefines from normally

gaseous materials such as propane, methane and mixtures thereof, we find it possible to utilize a reduced crude. Such a material is not only plentiful and has a relatively fixed and low cost, but, as will hereinafter be pointed out, it can also be cracked to a significantly high yield of olefins.

As heretofore determined, such material is unsuited for any direct conversion to olefins. We have found, however, that when the residue is decarbonized, by the removal of solid coke of commercial grades, the overhead vapors plus superheated steam make an unusually satisfactory charge to a regenerative furnace first because of the improved hydrogen-carbon ratio of the vapors and second because of the improved volatility of the product as a result of the decarbonization of the charge.

The coker section thus includes as a primary step, any of the well known coke production units whether of the continuous gravity type shown by the Schutte Patent 2,561,334 or of the "fluid" type or of the more generally used "delayed" coker type. For purposes of explanation, the latter type is illustrated but it will be understood that this is only one of the types that may be used.

With a reduced crude, vacuum bottoms or coal tar which may have a range of 0.20° API and from 0.7% sulfur, it is first desirable to heat the oil to about 200-400° F. so that it can be effectively handled. This oil is then passed in line 10, through a coil 11a in the tubular heater 11 wherein it is further heated and is then passed through line 12 to a flash tower 13. As will be herein-after described, the light ends are flashed from this material and the fuel oil residue is removed through line 14 and then pumped through a second coil 11b in the heater 11, or it can be taken off as product through line 14c as desired.

In coil 11b, the fuel oil is heated to around 900-950° F. and under such a pressure that when it passes through transfer line 15 into a coke drum 17, the solid coke will form in the well known manner.

Usually two or more coke drums 17 and 17a are used in parallel with switch valve 18 directing the material first into one drum and then into the other while the first is being cleaned out. Coke is removed through lines 19 or 19a and the overhead is removed at 20 or 20a.

The coker overhead which is removed at about 800 to 900° F., is introduced through line 21 into the lower part of flash tower 13 and thereby aids in driving off the light ends from the fuel oil removed at the bottom. As will be noted, this fuel oil, if there is any excess over coking requirements, may be used as heater fuel through line 14b.

The overhead in line 22 from the flash tower 13 then becomes the charge to the regenerative furnace 23. In general when processing a reduced crude with 10-20% Conradson carbon, the overhead contains in the order of 50-60% of a gas oil fraction having a boiling range of 350-850° F.; a gasoline fraction of around 10-15% of a boiling range of C₅ to 350° F. and approximately 5 to 15% of normally gaseous material. The coke already removed accounts for about 20-30%—all being based on original charge.

Regenerative furnace system

As a specific example of regenerative furnace, reference is made to the article entitled "Acetylene from Hydrocarbon Feed Stocks" in Industrial and Engineering Chemistry, vol. 45, page 2596.

Such a furnace is of box-type construction and is lined with insulation and refractory material. The inside of the furnace, except for a small combustion zone at the center, is filled with refractory tiles of special design. The ends of the furnace are provided with plenum boxes and baffles for the proper distribution of feed to the furnace.

Exhaust steam is superheated and mixed with the coker vapors before entering each pair of furnaces.

These furnaces are operated in pairs on a regenerative cycle, heat being removed from the refractory tiles by the pyrolysis of the gas feed and restored by the combustion of fuel gas with preheated air. A complete cycle for each furnace consists of a pyrolysis step and a heating step in the forward direction followed by a pyrolysis step and a heating step in the reverse direction. Each step usually occurs for approximately one minute. The time of these steps may, however, be varied according to needs. A description of the complete cycle follows.

(a) The steam-gas mixture is introduced at the front end of a furnace, pyrolysis occurs and the cracked gas is withdrawn from the back of the furnace.

(b) Air is introduced at the front of the furnace and preheated by the refractory tile before the air reaches the combustion zone. Fuel gas is admitted to the combustion zone and hot combustion gas passes through the refractory tiles and out the back of the furnace.

(c) The pyrolysis step is repeated with the steam-gas mixture flowing in the opposite direction to that described in step (a), i.e. back to front.

(d) The heating part of the cycle is repeated and the air and combustion gases flow through the heater in the opposite direction to that described in step (b), i.e. back to front.

So that there will be a continuous acceptance of the vapors in line 22 and a like continuous discharge of cracked olefinic hydrocarbons from the furnace system 23, a pair of furnaces are employed with appropriate switch valves operating as disclosed in the afore-mentioned article.

Although the regenerative furnaces are generally operated at about one-half atmosphere absolute pressure, in both the heating and cracking cycles, when acetylene is the preferred product, we prefer to operate at one to two atmospheres absolute pressure when ethylene is the preferred product. The charge (hydrocarbon plus steam) rate is increased, in such operation, so that the time of residence of the feed is the same as it would be if the furnace were at one-half atmosphere absolute pressure.

The following table better illustrates furnace operating conditions where the major olefinic product desired is either ethylene or acetylene.

Preferred operating conditions in regenerative furnace

Major Olefinic Product	Total Pressure, Atmospheres Absolute	Steam Hydrocarbon Ratio, Lbs./Lb.	Residence Time, Seconds	Cracking Temperature, ° F.
Ethylene.....	1-2	0.5-2.0	0.05-0.15	1,500-1,800
Acetylene.....	1	3-6	0.02-0.08	1,800-2,200
Acetylene.....	½	2.5-5	0.02-0.08	1,800-2,200

It has been observed that the acetylene yield approaches the theoretical maximum as the steam-hydrocarbon ratio is increased but economic considerations limit the amount of steam to practical limits. Yields of acetylene under optimum conditions may vary from 25 to 40% by weight of hydrocarbon charge to the furnaces.

Where ethylene is the preferred major product an increase in feed rate also increases the production capacity of a given furnace. For instance, if the pressure is one atmosphere, the production capacity would be about double that at one-half atmosphere. However, if the pressure on the furnace is too high polymerization and loss of the olefins to higher molecular weight products can occur in the cooler parts of the checker work. Hence, the preferred choice of pressure is about one to two atmospheres.

Gas for combustion purposes within the pair of furnaces is provided from off-gas sources throughout the system and enters in line 24.

After rapid heating in the regenerative furnace to the reaction temperature of 1500°-1800° F. or higher depending on the products desired, the cracked hydrocarbons are automatically quenched to about 900° F. by the refractory mass in the heat side of the furnace as described in the afore-mentioned article.

To obtain further heat economies we have shown a waste heat superheater 25 in which the furnace exhaust gases in line 26 give up heat to steam entering in exchange relation through line 27. The cooled exhaust gases then pass to stack 28 while the superheated steam in line 29 is mixed with the vapors in line 22 for cracking and dilution purposes. Steam is used to prevent coking on the refractory tiles as well as a diluent to reduce polymerization of unsaturates, etc. A dry feed would cause a marked decrease in yield. Usually one pound of steam is used per pound of charge but this ratio may be varied as required.

The cracked effluent from furnace 23 which includes either a major portion of ethylene or acetylene depending upon furnace operating conditions and which has been partially quenched to halt further reaction is passed through line 30 to a quench and tar separator 31. Preferably water is used as the quench material being introduced through line 32. Tar, steam and other contaminants are removed through line 33.

Summary of yields from regenerative furnaces

Products	Lbs./100 Lbs. to Coker	Lbs./100 Lbs. to Furnace
H ₂	0.71	0.97
CO	0.98	1.31
CO ₂	3.09	4.24
CH ₄	9.25	12.7
C ₂ H ₂	0.80	0.41
C ₂ H ₄	30.31	41.6
C ₂ H ₆	1.15	1.58
C ₃ H ₈	0.86	1.18
C ₄ H ₁₀	12.18	16.7
C ₅ H ₁₂		
C ₆ 's	8.76	12.0
C ₇ 's	0.71	0.97
Aromatics	2.87	3.94
Tars	1.34	1.84
H ₂ S	1.39	1.91

Gas cleanup section

The quenched gas leaves the separator through line 34 and is temporarily retained in the sour gas holder 35, after which it is passed through line 36 to a compressor 37. From the compressor the gas goes to an absorber 38 by passage through line 39 and cooler 40. In the absorber, C₅'s and aromatics are removed as bottoms through line 41 with the net overhead of olefinic gases passing through line 42 to a second compressor 43. Absorption oil entering the absorber near the top through line 44 may be obtained from an absorption oil stripper 45 which is located in the recycle line 46 of flash tower 13. Steam enters the stripper 45 through line 47 with the absorption oil flow in line 44 to the absorber 38 passing through circulation pump 48, reboiler 49 and exchanger 50.

A portion of the absorber bottoms in line 41 may be forwarded to flash tower as a reflux with the remainder being diverted through line 51 to a rerun tower 52. Overheads from the tower 52 pass through line 53 to condenser 54 and accumulator 55. Distillate from the accumulator may be passed in part to the rerun tower as reflux in line 56 and in part to line 57 as product C₅'s and aromatics while gases from the accumulator 55 may pass in line 58 to join the absorber overhead gases in line 42. Bottoms from the rerun tower may pass in line 59 through cooler 60 to unite with bottoms in line 41 from absorber 38.

The absorber overhead gases in line 42 which have been compressed at 43 are passed through line 61 to an acidic acid removal section indicated generally at 62.

Within this section acid gases including H₂S and CO₂ may be removed in any well known manner.

Acetylene conversion and fractionation sections

- 5 From the aromatic removal stage and the acid gas removal stage the olefinic gases, including a major portion of ethylene and some acetylene, may pass through line 63 to an acetylene conversion system indicated generally at 64. Such a system is provided where the major product desired at the final output is ethylene. To accomplish the conversion the acetylenes in the gases in line 63 may be hydrogenated to olefins in any well known manner. Impurities of the acetylenes conversion may be removed at 65.
- 10 The gaseous olefins pass from the acetylene conversion system through line 66 and are compressed at 67 prior to entering fractionation system 68. The compressed gases including a major percentage of ethylene in our preferred embodiment are fractionated in a known manner which may include two or more stages of fractionation (not shown). In such a fractionation system aromatics would be generally removed as tower bottoms with tower overheads including ethane, ethylene, propane, propylene and C₄ hydrocarbons removed to recovery 25 apparatus for separation into product gas streams 69, 70, 71 and 72 which may include off gas or recycle, ethylene, propylene and a C₄ cut.

- When recovering a 41% ethylene yield and a 65% total olefin yield from the total regenerative furnace product, 30 the principal furnace and tower operating conditions are those shown in the following tabulation.

Summary of furnace and tower operating conditions

Designation	Pressure, p.s.i.g.	Temperature, ° F.		
		Bottoms	In	Out
Preheater Coil 1			300-400	700-800
Coking Heater Coil 2				900-950
40 Coke Drums	20-35		900-950	800
Flash Tower	15-30	700-770	800-850	700-770
Regenerative Heater	1-5		700-770	900
Quench Separator	0-4		900	100

¹ Charge to flash tower.

² Charge to coker.

45

- If it is desired to produce a high yield of acetylene, the reaction temperature of the furnaces may be increased to the optimum temperature range of 1800 to 2200° C. and about 1/2 atmosphere absolute pressure with high 50 steam dilution under which circumstances the yield of acetylene will be in the order of 29% for a total yield of olefins of in the order of 58%.

- While we have shown and described a preferred form of embodiment of our invention, we are aware that 55 variations may be made thereto and we therefore desire a broad interpretation of our invention within the scope of the disclosure herein and the following claims.

We claim:

1. The process for thermally treating a heavy hydro-60 carbon charge to simultaneously produce coke and predominant yields of gaseous unsaturated hydrocarbons having less than four carbon atoms to the molecule: which comprises preheating said hydrocarbon charge to a temperature below its cracking temperature and in the order of about 700 to 800° F.; introducing said preheated charge into a flash zone wherein light ends are flashed from said preheated charge; withdrawing as a bottom stream from said flash zone normally liquid hydrocarbons having a boiling range of heavy fuel oil; heating said 65 bottoms to about 900 to 950° F. and introducing said heated bottoms, a portion of which is in the vapor phase, into a coking zone; maintaining the temperature and pressure in said coking zone so as to mildly crack the liquid portion of said heated bottoms whereby the un-70 vaporized portion of said bottoms is ultimately converted

75

to dry coke and additional vapors; withdrawing overhead vapors from said coking zone and introducing said vapors to said flash zone at a point below the point of introduction of said preheated charge whereby, during contact with said preheated charge, said light ends are flashed from said charge and the heaviest liquid constituents of said vapors having a boiling range of fuel oil are condensed; withdrawing noncondensed vapors including gas, gasoline and gas oil and said light ends from the upper part of said flash zone; mixing said noncondensed vapors and light ends with superheated steam and passing the mixture through a cracking zone in direct heat exchange contact with a hot thermally regenerated refractory mass contained therein; maintaining said mixture in said cracking zone for a period of from a fraction of a second to several seconds; maintaining the temperature of the refractory material in said cracking zone in the range from 1500 to 2200° F. thereby producing an effluent containing a high percentage of unsaturated hydrocarbons having less than four carbon atoms to the molecule; quenching said effluent; separating as product said unsaturated hydrocarbons from said quenched effluent; and withdrawing dry coke from said coking zone as product.

2. The process for thermally treating a heavy hydrocarbon charge to simultaneously produce coke and predominant yields of gaseous unsaturated hydrocarbons having less than four carbon atoms to the molecule as claimed in claim 1 wherein said flash zone is maintained under a pressure of about 15 to 30 p.s.i.g. and said coking zone is maintained under a pressure of about 20 to 35 p.s.i.g.

3. The process for thermally treating a heavy hydrocarbon charge to simultaneously produce coke and predominant yields of gaseous unsaturated hydrocarbons having less than four carbon atoms to the molecule as claimed in claim 1 wherein the mixture passing through the regenerative cracking zone is heated to from about 1500 to 1800° F. and the predominant unsaturated hydrocarbon contained in the cracking zone effluent is ethylene.

4. The process for thermally treating a heavy hydrocarbon charge to simultaneously produce coke and predominant yields of gaseous unsaturated hydrocarbons having less than four carbon atoms to the molecule as claimed in claim 1 wherein the mixture passing through the regenerative cracking zone is heated to from about 1800 to 2200° F. and the predominant unsaturated hydrocarbon contained in the cracking zone effluent is acetylene.

5. The process for thermally treating a heavy hydrocarbon charge to simultaneously produce coke and predominant yields of gaseous unsaturated hydrocarbons having less than four carbon atoms to the molecule: which comprises preheating said hydrocarbon charge to a temperature below its cracking temperature and in the order of about 700 to 800° F.; introducing said preheated charge into a flash zone wherein light ends are flashed from said preheated charge; withdrawing as a bottom stream from said flash zone normally liquid hydrocarbons having a boiling range of heavy fuel oil; heating said bottoms to about 900 to 950° F. and introducing

said heated bottoms, a portion of which is in the vapor phase, into a coking zone; maintaining the temperature and pressure in said coking zone so as to mildly crack the liquid portion of said heated bottoms whereby the unvaporized portion of said bottoms is ultimately converted to dry coke and additional vapors; withdrawing overhead vapors from said coking zone and introducing said vapors to said flash zone at a point below the point of introduction of said preheated charge whereby, during contact with said preheated charge, said light ends are flashed from said charge and the heaviest liquid constituents of said vapors having a boiling range of fuel oil are condensed; withdrawing noncondensed vapors including gas, gasoline and gas oil and said light ends from the upper part of said flash zone; mixing said noncondensed vapors and light ends with superheated steam and passing the mixture through a cracking zone in direct heat exchange contact with a hot thermally regenerated refractory mass contained therein; maintaining said mixture in said cracking zone for a period of from a fraction of a second to several seconds; maintaining the temperature of the refractory material in said cracking zone in the range from 1500 to 2200° F. thereby producing an effluent containing a high percentage of unsaturated hydrocarbons having less than four carbon atoms to the molecule; quenching said effluent; passing said quenched effluent through a contact with a light absorption oil whereby aromatics and C₅₊ hydrocarbons in said effluent are absorbed by said absorption oil; separating said effluent, free of aromatics and C₅₊ hydrocarbons, into normally related gaseous hydrocarbon constituents; fractionating said normally related constituents into separate gaseous unsaturated hydrocarbon products; and withdrawing dry coke from said coking zone as product.

6. The process for thermally treating a heavy hydrocarbon charge to simultaneously produce coke and predominant yields of gaseous unsaturated hydrocarbons having less than four carbon atoms to the molecule as claimed in claim 5 wherein the light absorption oil passing through the contact with said quenched effluent comprises a side stream from said flash zone and a portion of said absorption oil, after said contact, including absorbed aromatics and C₅₊ hydrocarbons is passed to the top of said flash zone as reflux.
